Primary Examiner—James Gandy*Assistant Examiner*—Elizabeth Albert(74) *Attorney, Agent, or Firm*—Michael Best & Friedrich LLP(57) **CLAIM**

We claim the ornamental design for a latch of a circular saw, as shown and described.

DESCRIPTION

FIG. 1 is a perspective view of a latch of a circular saw embodying aspects of the present invention;

FIG. 2 is a right side view of the latch of the circular saw of FIG. 1;

FIG. 3 is a rear view of the latch of the circular saw of FIG. 1;

FIG. 4 is a left side view of the latch of the circular saw of FIG. 1; and,

FIG. 5 is a top view of the latch of the circular saw of FIG. 1.

The broken line showing of the environment is for illustrative purposes only and forms no part of the claimed design.
